3 Claims. (Cl. 100—47)

ABSTRACT OF THE DISCLOSURE

Calender, especially for satinizing paper in which a plurality of moveable rolls are arranged in superposed relation above a stationary roll with a hydraulic unit connected to each end of the uppermost roll, each unit having a downwardly acting larger surface and an upwardly acting smaller surface, and with fluid pressure means connected to said surfaces and with valve means being provided for exhausting the upper surface so that the hydraulic units can lift the rolls, or pressurizing both surfaces so the rolls are urged downwardly into pressure engagement with each other.

The present invention relates to a calender, especially for satinizing paper, and more specifically concerns hydraulic means used in connection therewith for exerting pressure on the calender rollers.

With satinizing calenders it is known to employ double-acting fluid operable cylinder piston systems for exerting pressure on the rollers to selectively press the rollers against each other or lift the same from each other.

Heretofore known arrangements of the type set forth above have the drawback that with large and wide satinizing calenders, a low hydraulic pressure only is required for pressing the rollers against each other—in view of the considerable weight of the pressing roller—while a rather high hydraulic pressure is required to lift the pressing roller off the adjacent roller. Inasmuch as both pressures have to be furnished by the same hydraulic unit, it was necessary heretofore, when exerting pressure upon the rollers, to reduce the pressure in the hydraulic unit. Aside from the fact that this brings about a loss in the pumping energy, it is particularly disadvantageous that a relatively long time is required to bring the pressure from the low pressure value up again to the high pressure value for lifting the rollers from each other. This fact represents a considerable drawback, particularly when inserting a paper web, because, during such inserting operation, frequent short successive lifting and lowering operations with corresponding exertion of pressure have to be effected.

Another drawback of the heretofore known arrangements of the above-mentioned type consists in that when exerting low pressure and also when lifting the rollers from each other, due to the different friction in the guiding means for the bearings in the framework, the rollers can no longer be lifted or lowered synchronously, and the pressure exerted upon the two roller ends will generally differ. This, in turn, may bring about tilting of the rollers and jamming.

Still another drawback of the above-mentioned heretofore known arrangement consists in that it is not possible to exert different pressures upon both calender sides, as is sometimes desirable in practice.

It is, therefore, an object of the present invention to provide a calender, especially for satinizing paper, which will overcome the above-mentioned drawbacks.

It is another object of this invention to provide a calender with a hydraulic lifting and lowering system in

2

which the pressure furnished by the pressure source remains substantially the same during lifting and lowering of the respective roller or rollers.

It is still another object of this invention to provide a calender with hydraulic lifting and lowering means, which will make it possible to exert different pressures on the two ends of a calender roller.

A further object of the invention consists in the provision of a calender as set forth in the preceding paragraphs, which will automatically assure a synchronous movement of the ends of the respective calender roller.

These and other objects and advantages of the invention will appear more clearly from the following specification in connection with the accompanying drawing diagrammatically illustrating a calender according to the present invention.

A calender according to the present invention is characterized primarily in that individual hydraulic cylinder piston means are respectively provided for each calender side, while conduits and control means are so arranged and associated with said hydraulic cylinder piston means that each hydraulic cylinder piston means can be effective for that side of the calender only to which the respective hydraulic cylinder piston system pertains.

25 Referring now to the drawing in detail, the calender illustrated therein comprises a chilled cast roller 1, a plurality of elastic rollers 2 and chilled cast rollers 3 of considerably smaller diameter than roller 1. At both sides of the calender above the set of rollers 1, 2 and 3 there are respectively arranged two double-acting cylinder piston systems each comprising a cylinder 4, a piston 5 reciprocably mounted in cylinder 4, and a connecting rod 5' having its upper end connected to piston 5 and having its lower end connected to the bearing means 2' for the uppermost roller 2. As will be seen from the drawing, piston 2 is a double-acting piston having a larger effective top surface and a smaller effective bottom surface. It will be appreciated that when pressure fluid is conveyed both to the top surface and the bottom surface of piston 5, the differential pressure acting on piston 5 will press the rollers 2, 3 and 1 against each other. On the other hand, when pressure fluid acts upon the bottom surface only of piston 5, connecting rod 5' will lift the various rollers off from each other. This lifting off operation is effected by a lifting spindle 6 in cooperation with adjusting nuts 7 and 7'. More specifically, when piston 5 moves upwardly, an arm 2a of the bearing for the uppermost roller 2 engages a nut 7' threadedly connected to spindle 6 and thus lifts spindle 6 upwardly. After spindle 6 has been lifted by a distance a , that nut on spindle 6 which is adjacent to the uppermost roller 3 engages arm 3a of the bearing means for said last-mentioned roller, so that any further lifting movement of spindle 6 will lift said roller 3. Similar to the manner just described, all the other rollers will successively be picked up by the respective nuts on spindle 6 so that the various rollers will be spaced from each other. The nuts 7 are so adjusted that in the uppermost position of piston 5, substantially the same free gap will exist between all adjacent rollers.

60 When it is desired to have the various rollers in disengagement and spaced as just described for a longer period of time, spindle 6 may be provided with additional nuts 9 spaced from each other, while a valve 8 is adapted selectively to be actuated so as to have a plunger 8' thereof engage the space between the nuts 9 to thereby hold spindle 6 in its uppermost position.

Nuts 7 are, of course, adjustable in conformity with the desired spacing. As is evident from the drawing, while the left-hand side of the drawing may represent the control arrangement for the left-hand side of the various rollers, the arrangement comprises a corresponding control arrangement for the right-hand side of the

rollers, as shown in the drawing, and corresponding parts have been designated with the same reference numerals.

Hydraulic cylinder piston systems 4 are respectively hydraulically connected with hydraulic fluid sources I and II for producing and storing the respective desired hydraulic pressure. Each of said hydraulic units comprises a pressure pump 10, a fluid pressure storing vessel 11, a pressure gauge 12 and a pressure fluid container 13. As will be evident from the drawing, pressure is conveyed to cylinder 4 through pressure conduits 14 and 15 and a hydraulic reversing valve 20 for the pressure above piston 5 and a hydraulic reversing valve 21 for the pressure below piston 5.

When in conformity with the invention, the rollers are to be pressed against each other at a low pressure, both hydraulic units 20 and 21 are made effective so that the differential pressure corresponding to the cross-section of the piston rod will be effective upon the rollers. The adjustment for the maximum hydraulic pressure is effected by actuation of position indicators in contact gauges 12 which are adapted to switch on and off the pressure pumps 10.

Inasmuch as in case of a breakdown in the hydraulic units, especially pressure conduits 18 and 19, it may occur that the pressure cylinder will be subjected to full pressure only above piston 5 so that imprints may occur on the elastic rollers, there is, in conformity with the present invention provided a safety arrangement. This safety arrangement consists of an overflow conduit 22 with a check valve 24 interposed between the cylinder chambers above and below pressure piston 5. This check valve 24 is so designed that the pressure in the pressure chamber above piston 5 is adapted to equalize through a choke 25 with the cylinder chamber below piston 5.

According to a further development of the present invention, the hydraulic units have associated therewith an electric, hydraulic, or mechanical synchronizing arrangement in order to prevent one calender side from being lifted or lowered faster than the other calender side in view of different conditions of friction, whereby a jamming of the roller bearings may occur.

According to the drawing, the said synchronizing device is designed as an electro-hydraulic synchronizing device which comprises two potentiometers 26 and 27 respectively connected to the bearing means 2' for both sides of the uppermost roller 2. In addition thereto, the synchronizing device comprises a differential relay 28, which latter is adapted to open and close magnetic valves 29 and 30 provided in the pressure conduits 16 and 17 leading to the cylinder chambers above piston 5. The differential relay is connected to a slide contact 26a, 27a cooperating with that part of the potentiometer 26, 27 which is connected to the bearing means 2' for the uppermost roller.

From the above it will be evident that if one piston 5, for instance the left-hand piston 5, moves downwardly at a somewhat higher speed than the piston in cylinder 4 on the right-hand side, the current in the left-hand coil of the differential relay will prevail whereby central contact member 28a which normally occupies an intermediate or zero position, will close valve 29 thereby somewhat retarding the transmittal of pressure until synchronization is established with the other cylinder and contact 28a has returned to its intermediate or zero position.

When the roller set is lifted, it has heretofore been noted that following the frequent turning or machining of the rollers, unnecessarily large lifting movements are carried out when the pistons 5 are permitted to move to their respective end position. In order to overcome this drawback, according to a further feature of the present invention, the last-but-one roller (when looking downwardly) on each side of the calender, has its bearing 2' provided with a preferably adjustable contact 31 which by engagement with a contact member 33 closes a circuit for a magnetic valve 31', 32' respectively when roller 2

adjacent roller 1 has been spaced from the latter by the desired distance, which means that the uppermost roller has reached its maximum height. By closing the circuit for the magnetic valves 31', 32' through contact 31, the valves, respectively interposed in pressure conduits 18 and 19, are closed, so that no further lifting movement of pistons 5 and of the rollers can be effected. In other words, in this way any superfluous lifting operation will be eliminated regardless of the respective diameter of the rollers or other ground-off condition.

As will be evident from the foregoing description in connection with the accompanying drawing, it is possible, in conformity with the present invention, by simultaneously subjecting both roller sets to pressure, to press the rollers against each other at a rather low pressure in spite of the high pressure in the hydraulic units. This advantage is brought about by the fact that only the differential pressure in conformity with the piston rod is effective for pressing the rollers against each other. On the other hand, the present invention makes it possible to adjust the frequently necessary small pressure differences between the two calender sides.

It is, of course, to be understood that the present invention is, by no means, limited to the particular construction shown in the drawings, but also comprises any modifications within the scope of the appended claims.

What I claim is:

1. In a calender, especially for satinizing paper; a stationary roll and a plurality of moveable rolls arranged with their axes parallel and in superposed relation, a hydraulic operating unit at each end of the moveable roll most remote from the stationary roll and connected to the said remote roll so as to move it in a direction toward the stationary roll or in a direction away from the stationary roll, lost motion connections between said moveable rolls whereby upon movement of said remote roll in a direction away from said stationary roll the moveable rolls will all be moved into spaced relation to each other and to said stationary roll, whereas upon movement of the remote roll toward said stationary roll all the said rolls will interengage, each hydraulic operating unit comprising a working piston connected to the remote roll and having a larger surface responsive to fluid pressure for moving the remote roll toward said stationary roll and also having a smaller surface opposed to said larger surface, substantially constant pressure fluid source means connected to each of said larger surfaces by a respective first conduit and to each of said smaller surfaces by a respective second conduit, a normally open electrically operable valve in each of said first conduits, a differential switch having opposed electrical operators and operable to energize the electrically operable valve in one of said first conduits when a certain one of the electrical operators becomes predominant over the other thereof, a rheostat in circuit with each of said operators, means connected to respective ends of said remote roll for adjusting respective ones of said rheostats as the remote roll is moved toward said stationary roll, and control means including valve means connecting said source means with the said larger and smaller surfaces of both of said hydraulic operating units and operable for supplying fluid under pressure to both of the said surfaces of each unit for pressing said rolls against each other or for exhausting the larger surfaces of both of the units for causing said rolls to be separated from each other.

2. A calender according to claim 1 in which said fluid source means is connected to each of said larger surfaces by a respective first conduit and to each of said smaller surfaces by a respective second conduit, a normally open valve in each of said second conduits, an electric actuator for each of said valves, and means operable in response to a predetermined separating movement of said rolls for energizing said actuators to interrupt the said separating movement.

3. A calender according to claim 1 in which bypass channel means are provided leading from each larger surface to the respective smaller surface and preventing fluid flow from the smaller surface to the larger surface while permitting fluid to flow slowly from the larger surface to the smaller surface. 5
